Int. Cl. D23—04

U.S. Cl. D23—142

FIG. 1 is a front elevational view of a louvered outlet for an automobile air conditioner embodying my new design.

FIG. 2 is a perspective view of a modified form thereof with the louvers tilted downwardly.

FIG. 3 is a perspective view of a form shown in FIG. 2 with the louvers tilted upwardly.

FIG. 4 is a view in perspective showing both my embodiments embodied in a dashboard, said dashboard and one outlet being shown in broken lines for illustrative purposes only.

I claim:

The ornamental design for a louvered outlet for an automobile air conditioner, substantially as shown and described.
